UNITED STATES PATENT OFFICE.

FRANCIS J. ZIPPLER, OF AVALON, PENNSYLVANIA, ASSIGNOR OF ONE-HALF TO
CHARLES M. HOFFERT, OF READING, PENNSYLVANIA.

PISTON.

1,365,578.

Specification of Letters Patent. Patented Jan. 11, 1921.

Application filed May 8, 1920. Serial No. 379,801.

To all whom it may concern:

Be it known that I, FRANCIS J. ZIPPLER, a citizen of the United States, and a resident of Avalon, in the county of Allegheny and State of Pennsylvania, have invented a new and useful Improvement in Pistons; and I do hereby declare the following to be a full, clear, and exact description thereof.

My invention relates to pistons, and has special reference to what are known as hollow pistons, such as are used in internal combustion engines for automobiles etc.

These pistons are generally provided with split piston or packing rings for engaging with the interior wall of the cylinder, and the main object of my invention is to provide a cheap, simple and efficient form of a piston, which will enable such rings to adhere more closely against the interior wall of the cylinder, and thus prevent the compression or explosive mixture from passing between such rings and said cylinder wall, thereby overcoming loss of compression and the power incident thereto.

Various other objects, such as durability, cheapness in manufacture, and the general improvement of the art are also provided for and will be brought out in the following specification and illustrated in the accompanying drawing.

To these ends my invention consists, generally stated, in the novel arrangement, construction and combination of parts, as hereinafter more specifically set forth and described and particularly pointed out in the claims.

To enable others skilled in the art to which my invention appertains to construct and use my improved piston, I will describe the same more fully, referring to the accompanying drawing, in which—

Figure 1 is a side elevation of a hollow piston having my invention applied thereto and showing the piston within the cylinder, which is in section;

Fig. 2 is a like view but showing the piston in section, and taken on the line 2—2 Fig. 1, looking in the direction of the arrows;

Fig. 3 is a top view of the piston and showing the cylinder in cross-section;

Fig. 4 is a cross-section of the piston and cylinder, taken on the line 4—4 Fig. 2 and looking in the direction of the arrows, and 55

Fig. 5 is a view of the supporting ring employed.

Like symbols of reference herein indicate like parts in each of the figures of the drawing.

As illustrated in the drawing 1 designates the piston, which is provided with the annular hollow piston or chamber 2 within the same, with the side walls 3 surrounding such portion and end walls 4 over the same. 65 Within such hollow portion 2 is the usual wrist-pin 5, which extends across the same and is supported in bearings 6 formed in the side wall 3. Within the side walls 3 of the piston 1 and at one end of the same 70 is the annular seat or groove 7 for the reception of the usual piston or packing ring 8, which is movable around and within said seat and is of the well known split form. At the other end of the piston 1 75 and within the side walls 3 and adjacent the end wall 4 is the annular seat or groove 9, which is of greater depth and length than the seat 7 and has a plurality of openings 10 leading through said side walls. Each 80 of the openings 10 communicate with an inclined groove or passage-way 11 formed in the end wall 4 of the piston 1 and leading from the face of said end wall inwardly to the inner end of said openings. Within 85 the seat 9 is the master or supporting ring 12, which is of the split form, by being formed in a single section and connected together at end portions 13 by a miter or oblique lapped joint 14, and such ring is 90 provided with lug portions 15 on its inner face, each of which extends into each of the openings 10. These lug portions 15 act to keep the ring 12 in position in the seat 9, so that the joint 14 on the ring will not 95 register with the openings 10 by moving along the seat in front of such openings. The openings 10 are smaller in depth than the seat 9 in order to form shoulders 10' in the side walls 3, for fitting over the lugs 15 and against which the ring 12 bears in order to overcome any loss of compression by preventing the explosive mixture from passing around the edges of the said lugs

2
and ring and through said openings from the grooves 11. The ring 12 is provided with an annular flange 16 extending out from the outer face of the same, which acts 5 to form the two seats 17' between the same and the ends of the groove 9, and within each of said seats is the piston ring 17 for bearing against the cylinder wall *a* of the cylinder. These piston rings 17 are of the 10 usual split form and have the single section connected together at their end portions 18 by a miter or oblique lapped joint 19, and such rings are movable around the seats 17' in bearing against the cylinder wall *a*.
15 The lugs 15 on the supporting ring 12 are formed slightly smaller than the openings 10 in order to allow sufficient play or clearance in the openings to prevent binding therein and permit the operating fluid to 20 strike the same, thereby forcing the ring 12 outward to enable the ring 17 to come against the cylinder wall *a*.

In operation of my improved piston 1 within the cylinder A, such piston will 25 travel in the usual back and forth movement therein by reason of the explosive mixture striking the end of the piston in the usual manner, and in order to move the piston rings 17 against the cylinder wall *a*, 30 a portion of such mixture will pass through the passage-ways or grooves 11 and impinge against the rear face of the lugs 15 on the supporting ring 12, and this action of the explosive mixture will press the ring 35 12 and rings 17 mounted on the outer face of said ring 12 outward, so that the rings 17 will come against the cylinder wall *a* and thus prevent any of such mixture passing by and between said rings, piston wall 3 40 and said cylinder wall.

Various modifications and changes in the design and construction of my improved piston may be resorted to, without departing from the spirit of the invention or sacrificing 45 any of its advantages.

It will thus be seen that the use of my improved piston will provide a tight fit of the same to the cylinder bore or wall, and will enable the outer piston or packing 50 rings used with the same to be worn down to a small thickness before requiring renewal.

It will also be seen that the outer piston or packing rings will engage the cylinder bore or wall more closely and without much friction between the parts, and enable the full force of the explosive mixture to act in moving the piston, yet at the same time prevent leakage of such mixture along these piston rings, and thereby overcome any loss of power in moving the piston by such leakage.

What I claim as my invention and desire to secure by Letters Patent is:

1. An internal combustion engine piston having its outer side walls provided with

a seat within the outer face of the same and openings in said seat extending through said wall, said piston having its end wall provided with grooves leading to said openings, a supporting split ring within said 70 seat, split piston rings carried by said first named ring, and lug portions on said first named ring extending into said openings and adapted to hold the split portion of said ring away from said openings, said lug 75 portions being adapted to receive a portion of the operating fluid passing through said grooves for forcing said rings outward and said last named rings against the cylinder wall.

2. An internal combustion engine piston having its outer side walls provided with a seat within the outer face of the same and openings in said seat extending through said wall, said piston having its end wall provided with grooves leading to said openings, a supporting split ring within said 80 seat, split piston rings carried by said first named ring, lug portions on said first named ring extending into said openings and adapted to 85 hold the split portion of said ring away from said openings, said lug portions being adapted to receive a portion of the operating fluid passing through said grooves for forcing said rings outward and said last 90 named rings against the cylinder wall, and shoulders on said side wall extending into said openings for fitting around said lug portions and for bearing against said first named ring. 10

3. An internal combustion engine piston having its outer side wall provided with a seat within the outer face of the same and openings in said seat extending through said wall, said piston having its end wall 10 provided with grooves leading to said openings, a supporting split ring within said seat having a flange extending out from the same, split piston rings carried by said first named ring, and lug portions on said first 11 named ring extending into said openings and adapted to hold the split portion of said ring away from said openings, said lug portions being adapted to receive a portion of the operating fluid passing through said 11 grooves for forcing said rings outward and said last named rings against the cylinder wall.

4. An internal combustion engine piston having its outer side walls provided with a 1 seat within the outer face of the same and openings in said seat extending through said wall, said piston having its end wall provided with grooves leading to said openings, a supporting split ring within said 1 seat, split piston rings carried by said first named ring and supported by said wall and flange, lug portions on said first named ring extending into said openings and adapted to hold the split portion of said ring away 1

from said openings, said lug portions being adapted to receive a portion of the operating fluid passing through said grooves for forcing said rings outward and said last 5 named rings against the cylinder wall, and shoulders on said side wall extending into said openings for fitting around said lug

portions and for bearing against said first named ring.

In testimony whereof, I, the said FRANCIS 10 J. ZIPPLER, have hereunto set my hand.

FRANCIS J. ZIPPLER.

Witness:

J. M. GEOGHEGAN.
